UNITED STATES PATENT OFFICE

171,326

FRY PAN COVER

Henry G. Fornoff, Los Angeles, Calif.

Application September 21, 1953, Serial No. 26,873

Term of patent 14 years

(Cl. D44—15)

To all whom it may concern:

Be it known that I, Henry G. Fornoff, a citizen of the United States, residing in the city and county of Los Angeles and State of California, have invented a new, original, and ornamental Design for a Fry Pan Cover, of which the following is a specification, reference being had to the accompanying drawing forming part thereof.

Fig. 1 is a top perspective view of a fry pan cover, showing my new design.

Fig. 2 is a bottom perspective view thereof.

I claim:

The ornamental design for a fry pan cover, substantially as shown.

HENRY G. FORNOFF.
